CLAIM

We claim the ornamental design for a building automation device, as shown and described.

DESCRIPTION

FIG. 1 is a top, front, left perspective view of an embodiment of the claimed design;

FIG. 2 is a bottom, front, right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

Any portion of the article depicted in broken lines forms no part of the claimed design. The dash-dot-dash lines define the bounds of the claimed design and form no part thereof.

1 Claim, 6 Drawing Sheets
